UNITED STATES PATENT OFFICE.

LLEWELLYN F. BRYANT, OF LYNN, MASSACHUSETTS, ASSIGNOR TO THE SPRINGFIELD MOTOR SWEEPER COMPANY, OF SPRINGFIELD, OHIO, A CORPORATION OF OHIO.

STREET SWEEPER.

Application filed January 8, 1923. Serial No. 611,482.

To all whom it may concern:

Be it known that I, LLEWELLYN F. BRYANT, a citizen of the United States, residing at Lynn, in the county of Essex and State of Massachusetts, have invented certain new and useful Improvements in Street Sweepers, of which the following is a specification.

This invention relates to improvements 10 in sweeping apparatus, and more particularly to apparatus of this kind known as street sweepers in which a horizontal rotary broom is employed.

An object of the invention is to provide 15 for more thoroughly removing the sweepings from the street or other surface being swept.

A more specific object of the invention 20 is to provide means cooperating with a horizontal rotary sweeping broom which will prevent those sweepings which become packed in the bristles of the broom from being discharged rearwardly of the apparatus by centrifugal force and again deposited upon the swept surface.

In the accompanying drawings:

Fig. 1 is a side elevation of a street 25 sweeper embodying the improvements.

Fig. 2 is a view of one end of the horizontal broom showing my improvements in side elevation.

Fig. 3 is a rear elevation of a portion 30 of the parts shown in Fig. 2.

Referring to the drawings, a motor 35 driven street sweeper is shown in Fig. 1 which has a plurality of vertically-disposed sweeping brooms 1 arranged to throw the sweepings toward the center of the line of travel of the machine, and a rear horizontally-disposed broom 2, which rotates anti-clockwise, and picks up the sweepings from the forward brooms and deposits them on an elevator 3 by which they are carried to the hopper 4. The 40 shaft 5 of the horizontal broom is journaled in the rear ends of a pair of pivoted arms, one of which 6, is shown in Fig. 1, and provision is made for raising the broom by a hand lever 7 located near the 45 driver's seat, through the medium of the cable 8, attached to the crank arm 9, connected to shaft 10, a crank arm 11 also connected to said shaft, and a link 12 connecting the crank arm 11 with the arm 50 6. The shaft 10 extends to the opposite

side of the machine where similar connections are made with another arm corresponding to arm 6.

Heretofore, in the operation of these machines, when a large pile or accumulation 60 of dirt, leaves and other sweepings is encountered sufficient to overload the horizontal pick-up broom, a part of the sweepings will be packed into the wire bristles of the broom and be carried therewith and 65 discharged by centrifugal force rearwardly of the machine. To overcome this, I have provided means whereby such sweepings will be held in the bristles of the broom until they reach a point between the road 70 surface and the mouth or lower end of the elevator, at which point, if only the usual amount of sweepings is being encountered, they will be thrown out of the 75 bristles by centrifugal force and discharged onto the elevator in the usual way. The means consist of a cover or casing which encloses and tightly hugs that part of the periphery of the broom which would tend 80 to throw the sweepings contained within the bristles thereof rearwardly out of the path of the broom and is shown as extending from a point beginning with substantially the vertical center line of the broom at the top to a point near the ground 85 line at the bottom. In the present case the casing is formed in three sections 13, 14 and 15 having their adjacent edges hinged together and so shaped as to conform to the contour of the outer periphery 90 of the broom. These casing sections are preferably of light sheet metal and are arranged to tightly hug the bristles of the broom partly by their own weight and partly by springs, one of which is shown 95 at 16, which connects the sections 14 and 15 and draws the lower section 15 with a yielding pressure against the broom bristles. One of these springs is arranged at each end of the casing and shown as 100 connected with side enclosing walls 17 and 18 with which the sections 14 and 15 are preferably provided.

The casing thus formed is hung from the frame 19. A short rock shaft 20 has a crank 105 arm 21 which arm is pivotally connected with the middle section 14 of the casing by a link 22, the side wall 17 of said section having a lateral trunnion 23 which receives the link. The shaft 20 has attached thereto 110

another crank arm 24 which is connected by the rod 25 with the arm 9. Similar connections (not shown) are made from the opposite end of the rock shaft 10 to the opposite end of the middle section 14 of the casing. These connections between the arms 9 and the casing not only sustain the casing in proper relation with the horizontal broom but also serve to raise the casing when the broom is raised.

The space between the upper edge of the casing section 13 and the hopper 4 is enclosed at the rear by a flexible curtain 26 attached at its upper edge to the hopper 4 and at its lower edge to the upper edge of the casing section 13 in any suitable way. The hopper is of the tilttable type, being designed to roll back upon the track 27 in a well known way, the flexible curtain 26 collapsing or folding when the hopper tilts. This curtain prevents dust, dirt or other sweepings from being thrown rearwardly over the top of the casing by centrifugal action of the broom. A second flexible curtain or flap 28 is attached to the lower edge of the lower casing section 15 and closes the space between the same and the ground to prevent escape of the sweepings from the broom bristles at that point.

By this arrangement it will be seen that the upper and middle casing sections will be caused to closely hug the periphery of the broom substantially by the weight of the casing, the lower section being sustained in close proximity to the broom bristles by the springs. This casing prevents the dirt, leaves and other sweepings which are packed in the bristles from being thrown rearwardly by centrifugal force and insures that eventually practically all of the sweepings will be deposited onto the elevator and carried to the hopper.

Having thus described my invention, I claim:

1. In a sweeper, the combination, with a horizontally disposed broom arranged to throw the sweepings forwardly, and a casing

formed in hinged sections enclosing a portion of the periphery of the broom at the rear thereof, the lower section being resiliently connected with the adjacent upper section to hold said lower section in yielding contact with the periphery of said broom, the upper section being held in yielding contact with the periphery of the broom by the weight of said section.

2. In a sweeper, the combination of a horizontally-disposed broom arranged to throw the sweepings forwardly, a casing formed of hinged sections, together with yieldable means for holding all of said sections in yielding contact with the bristles of said broom at the rear thereof, for the purpose specified.

3. In a sweeper of the character described, the combination with a horizontally-disposed sweeping broom arranged to throw the sweepings forwardly, a casing arranged in yielding relation with the periphery of said broom at a point in the rear thereof, and means for simultaneously elevating said broom and casing.

4. In a sweeper of the character described, the combination with a horizontally-disposed sweeping broom, a casing arranged in yielding relation with the bristles of said broom at the rear thereof, said casing being formed in hinged sections, a hand lever and connections therefrom to said broom for elevating the same, and an additional connection to said casing for elevating said casing simultaneously with said broom.

5. In a sweeper, the combination, with a tilttable hopper, of a horizontal rotary broom, a casing for said broom arranged in close proximity to that portion of the periphery thereof opposite the discharge side of the broom, and a flexible curtain attached to said hopper and to the upper edge of said casing.

In testimony whereof, I have hereunto set my hand this 28th day of December, 1922.

LLEWELLYN F. BRYANT.
